UNITED STATES PATENT OFFICE.

JOHN C. GABEL, OF CHAMPAIGN, ILLINOIS, ASSIGNOR OF ONE-HALF TO CHARLES N. CADWELL, OF CHICAGO, ILLINOIS.

ELECTRICAL OFFICE-INDICATOR.

1,036,089.

Specification of Letters Patent. Patented Aug. 20, 1912.

Application filed June 5, 1911. Serial No. 631,207.

To all whom it may concern:

Be it known that I, JOHN C. GABEL, a citizen of the United States, and a resident of the city of Champaign, county of Champaign, and State of Illinois, have invented certain new and useful Improvements in Electrical Office-Indicators, of which the following is a specification.

My invention relates to improvements in electrical office indicators adapted to be placed adjacent an office door for informing callers when the office officials will return in case of their absence.

The object of the invention is to provide an office indicator of the character mentioned which shall be simple of construction, neat and compact in appearance, and efficient in operation.

Other objects will appear hereinafter.

With these objects in view my invention consists in the novel construction and arrangement of parts hereinafter described and claimed.

My invention will be best understood by reference to the accompanying drawings forming a part of this specification and in which,

Figure 1 is a front elevation of an office indicator embodying my invention, Fig. 2 a side elevation thereof, Fig. 2^a is an inside view of the cover of the indicator, Fig. 3 is a top plan view of said cover, Fig. 4 is an inside view of the body of the indicator, and Fig. 5 is a detail front elevation.

The preferred form of construction as illustrated in the accompanying drawings comprises a rectangular box or inclosure 1 which is formed of sheet metal and provided with an open front. This body is provided with an upwardly extending perforated ear or lug 2 by means of which the same is suspended to a wall or office door. The opening in the front of the box is closed by a vertically disposed cover 3 having side flanges 4 which engage the sides of the body 1 as clearly illustrated in Fig. 2. Depending from the front edge of the top of the body 1 is a flange 5 which overhangs the top edge of the cover 3 thus retaining the same when inserted therein as shown in Figs. 1 and 2. After the top edge of the cover 3 is inserted as described at its top end screws 6 are employed for securing the lower end of the

cover, said screws passing through the flanges 4 into the sides of the body 1. The front cover 3 bears adjacent its top the inscribed words "Electrical office indicator" and adjacent its center the words "Push button for information", the latter words being inscribed directly under a centrally disposed push button 7. This button is adapted to reciprocate in a horizontal plane and is held in the normal position as shown in Figs. 1 and 2 by means of a helical spring 8 surrounding a stem 9 which is secured to 65 and arranged in axial alignment with the button 7. The spring 8 forces the button 7 outwardly, and in order to limit this outward movement a flange 10 is provided at the inner end of the button 7 which engages 70 the inner surface of the cover 3, which construction is clearly illustrated in Fig. 3. The inner end of the push button stem 9 is bifurcated and guided by means of a perforation 11 formed in a sheet steel stamping 75 12, the latter having standards 13 which are secured at their lower ends 14 to the inner face of the cover 3 as illustrated in Fig. 3. Pivoted in the bifurcated end of the stem 9 is an arm 15 which is also bifurcated to 80 work freely over a pivotal pin 16 passing through the bifurcated end of the stem 9 as illustrated in Figs. 2 and 3. Arm 15 is formed integral with an oscillatory arbor 17 which is journaled in perforated ears 18 85 projecting from the stamping 12. The exterior ends 19 of the arbor 17 are bent forwardly and to the terminals of these ends are pivoted connecting rods or links 20 which extend downwardly and connect with 90 perforated lugs 21 projecting rearwardly from a vertically movable shutter 22. This shutter is guided in its vertical movement by means of vertically disposed guides 23 formed as clearly illustrated in Figs. 2^a and 95 3. The function of the shutter 22 is to open and close an elongated rectangular opening 24 formed adjacent the bottom of the cover 3 as illustrated in Fig. 1 and by dotted lines in Fig. 2^a. Secured to one side of a standard 13 of the stamping 12 is an insulator 25 to which is secured a metallic conductor 26 the end 27 thereof being resilient or in other words a flat spring the width of which is shown in Fig. 2^a. The end of the spring 27 105 is arranged in the path of movement of the

push button stem 9, the latter striking said spring prior to the end of its inward stroke. The conductor 26 is connected by means of a wire 28 to one terminal of an incandescent lamp socket 29 carrying the lamp 30. The other terminal 31 of the incandescent lamp socket 29 connects with the battery 32, the latter being preferably of the dry-cell type. The battery 32 is supported in the top of the body 1 by means of a bracket 22 and the other terminal 34 thereof is grounded to the body 1 by means of a wire 35.

From the construction of the push button and the connecting mechanism it is apparent that the same are in electrical connection with the body 1, consequently in order to complete the electric circuit of the battery 32 it is only necessary to push the push button stem 9 into contact with the spring terminal 27 as illustrated in Fig. 3. In doing this the lamp 30 effects the illumination of a rotatable drum 36 which is mounted adjacent the bottom of the body 1 and adapted to be rotated by means of a knurled handle 37 which projects from one side of the body 1 as illustrated in Figs. 1 and 4. The drum 36 is polygonal in cross section and provided with a plurality of card retaining longitudinally extending flanges 38 the end view of which is clearly shown in Fig. 2. The cards 39 carried by the drum 36 are inserted into the body 1 and positioned on said drum through a rectangular opening 40 provided in the body 1. Each face of the drum 36 may be provided with a card which may disseminate any information desired, the information being usually such as indicated in Fig. 4. A bearing shaft 41 which carries the drum 36 is closely fitted in a side of the box 1, the fit being such that the drum will be frictionally held in any position which it may assume. In the operation of the drum 36 it is only necessary to rotate the handle 37 sufficiently to bring the desired card to the front as shown in Fig. 4. On elevation of the shutter 22 and lighting of the lamp 30 this card may be readily read by a person pushing the button 7. In order to register the number of callers during the absence of a person from his office a registering disk 41' is provided, the same being mounted adjacent the stamping 12 as shown in Fig. 2. This disk is provided with a central arbor 42 which is journaled in the cover 3 of the indicator. The front face of the disk 41' bears numerals arranged consecutively as shown in Fig. 5, and one of which being shown in Fig. 1. This registering device is operated by means of a resilient arm 43 rigidly secured to the shutter 22 and extending upwardly therefrom as illustrated in Fig. 2. The upper end of the arm 43 is formed into an eye for proper engagement with one of a plurality of teeth 44 provided in the rear of the disk 41 and formed in-

tegral therewith. The disk 41' is rotated intermittently a distance corresponding with the spacing of one of the numerals thereof by means of the eye on the arm 43 which contacts with a tooth 44 at the limit of the upward movement of the shutter 22, the disk 41' being thus moved a distance corresponding with the spacing of the teeth thereon. During the downward movement of the shutter 22 the eye on the arm 43 is forced outwardly whereupon it escapes the tooth from which it has been in contact. This movement is obviously due to the inherent resiliency of the arm 43. Were no means provided to stop the rearward rotation of the disk 41' the downward movement of the arm 43 would cause as much retrograde movement as it had previously caused forward movement. To prevent this retrograde movement a stop pawl 45 which is secured at one terminal of a spring 46 is provided. The spring 46 is rigidly secured in a rearwardly extending bifurcated stud as illustrated in Fig. 2. From this construction it is apparent that the number of callers will be accurately registered, the rectangular opening 48 provided in the cover 3 rendering the numerals borne on the disk 41' visible. In order that the drum 36 may be illuminated in an efficient manner two reflectors 49 and 50 are provided the former being secured in the body 1 and the latter in the cover 2, as illustrated in Figs. 4 and 1 respectively.

In order that a caller may write a note to the party whom he wishes to interview a plurality of cards 51 are provided on the top of the body 1, said cards being held in position by means of a resilient clip 52. After a card 51 has been written on, the same is inserted in a supplementary clip 53 located above the clip 52 as clearly illustrated in Fig. 2. Still another clip 53' is provided at the bottom of the body 1 for the reception of mail matter, newspapers, etc.

The mode of operation of the device is as follows: Assuming that the push button 7 is in its projecting normal position as illustrated in the several views, then when the same is depressed the arm 15 will be so moved as to effect the elevation of the shutter 22 thus exposing to view the card 39 on the drum 36. Supposing that there is not sufficient light to render the card easily visible upon the opening of the shutter 22 it becomes necessary that the card should be illuminated. To accomplish this a lamp 30 is provided as hereinbefore described and the same is lighted when the inner end of the push button stem 9 contacts with the terminal 27, thus closing the battery circuit. The button 7 is held in the depressed position until the person has read the card on the drum 36 whereupon said button is re-

leased. Upon releasing the button 7 it automatically returns to the normal position as shown in the several views, it being obvious that the light will be extinguished 5 upon the breaking of the battery circuit.

An office indicator of the construction set forth is neat and compact in appearance, and renders useful service to the callers at an office.

10 While I have illustrated and described the preferred form of construction for carrying my invention into effect, this is capable of variation and modification without departing from the spirit of the invention.

15 I therefore do not wish to be limited to the precise details of construction set forth, but desire to avail myself of such variations and modifications as come within the scope of the appended claims.

20 Having described my invention what I claim as new and desire to secure by Letters Patent is:

1. A device of the class described comprising an open front box; a detached cover 25 for said box; a display member mounted in said box, there being an opening provided in said cover in front of said display member; a vertically movable shutter mounted upon said cover above said opening and normally closing the latter; a push-button provided in said cover above said shutter; a stem provided on said push-button and projecting into the interior of said box; a spring resisting depression of said push-button; an arbor mounted below the inner end 30 of said stem and carrying an arm pivoted to the latter; two arms mounted integrally with said arbor and projecting to the front therefrom; and a link connection between

said last named arms and said shutter, substantially as described. 40

2. In a device of the class described, the combination with a box having an open front and a detachable cover, of a display member mounted in said box, there being an 45 opening provided in said cover in front of said display member; a shutter mounted on the interior of said cover and normally closing said opening; a push-button mounted in said cover above said shutter; a stem 50 in axial alinement with said push-button and projecting into the interior of said box; operative connections between said stem and shutter for operating the latter; an electric incandescent lamp arranged adjacent said 55 display member and adapted to emit light for illuminating said member; a plurality of reflectors arranged adjacent said lamp and adapted to reflect light therefrom onto said display member; an electric battery, the 60 lamp being in the battery circuit, one terminal of said circuit being normally insulated from said stem, the latter being grounded to said battery, the arrangement being such that when said push-button is 65 depressed said stem will contact with said terminal for closing the lamp circuit; and a registering device arranged in operative connection with said shutter, substantially as described. 70

In testimony whereof I have signed my name to this specification in the presence of two subscribing witnesses.

JOHN C. GABEL.
